United States Patent Office

Des. 233,503

Patented Nov. 5, 1974

233,503

SPOON OR SIMILAR ARTICLE

Frank R. Perry, Oneida, N.Y., assignor to
Oneida Ltd., Oneida, N.Y.

Filed May 2, 1973, Ser. No. 356,339

Term of patent 14 years

Int. Cl. D7—03

U.S. Cl. D7—137

FIG. 1

FIG. 2

FIG. 3

FIG. 4

FIG. 5

FIG. 1 is a front view of a spoon or similar article showing my new design;

FIG. 2 is a rear view thereof;

FIG. 3 is a side view thereof, the undisclosed side being substantially identical with the side shown in FIG. 3;

FIG. 4 is an enlarged cross-section taken on line 4—4 of FIG. 1; and

FIG. 5 is an enlarged cross-section taken on line 5—5 of FIG. 1.

I claim:

The ornamental design for a spoon or similar article, substantially as shown and described.
